VALVE STEM PACKING

Delmar D. Robertson, Lansdowne, and George L. Briggs, Bryn Mawr, Pa., assignors to Wilkening Manufacturing Company, Philadelphia, Pa., a corporation of Delaware

Application December 24, 1935, Serial No. 55,980
Renewed August 23, 1938

10 Claims. (Cl. 286—1)

The present invention relates to packing or sealing means and it relates more particularly to valve-stem packing for use in internal combustion engines for effecting a seal between the reciprocating valve stem and the stationary valve stem guide.

An object of the present invention is to provide efficient and durable packing or sealing means intermediate the valve stem, the valve stem guide in an internal combustion engine or the like, which will effectively seal against the passage of gases and liquids through the greater or lesser clearances commonly present between the valve stem and the guiding aperture in which the valve stem is slidably mounted for its reciprocating movement.

A further object of the present invention is to provide valve stem packing or sealing means of the character stated, which, while effectively and durably sealing between the valve stem and its retaining guide aperture, will nevertheless not impose any undue friction upon the valve stem, and which will not materially increase the resistance of the valve stem to its operative movements, and which will not in any way disturb, alter or affect the spring tensioning of the valve which is predetermined in the original design of the engine (as for instance, where the device of the present invention is applied to engines initially designed and built without any valve stem packing or sealing means.)

With the above and other objects in view which may appear more fully from the following detailed description and accompanying drawings, the present invention consists of valve-stem packing means comprising a certain novel combination of retaining means and sealing means associated with the valve stem guide in a novel manner whereby the valve stem packing or sealing means may be maintained in operative relation to the valve stem guide without any supplemental or auxiliary devices, such as springs, screws, etc.

The present invention further consists of a certain novel co-relationship between valve stem packing means and valve stem guide, whereby a positive interlocking engagement is obtained between the valve stem guide and valve stem packing or sealing means without external aid or without the aid of external fastening means or retaining means.

The present invention further consists of certain novel features and details of construction in a valve stem packing cage and certain novel combination of valve stem sealing means therewith.

The present invention further consists of other novel features and details and relationships, which may appear more fully in the following detailed description and accompanying drawings.

For the purpose of illustrating the invention, there is shown in the accompanying drawings one

form thereof which is at present preferred, since the same has been found in practice to give satisfactory and reliable results, although it is to be understood that the various instrumentalities of which the invention consists can be variously arranged and organized and that the invention is not limited to the precise arrangement and organization of the instrumentalities as herein shown and described.

In the accompanying drawings in which like reference characters indicate like parts:

Figure 1 represents a fragmentary perspective view, on a much enlarged scale, of the valve-stem packing and sealing means embodying the present invention, with part of the packing or sealing means broken away and shown in section.

Figure 2 represents a fragmentary perspective view of a sealing means adapted to be substituted for that shown in Figure 1, but of somewhat different construction.

Figure 3 represents a horizontal sectional view taken on the line 3—3 of Figure 6, the scale being intermediate that of Figure 1 and that of Figure 6.

Figure 4 represents a section on line 4—4 of Figure 3.

Figure 5 represents a perspective view of the retaining cage alone, on a somewhat smaller scale.

Figure 6 represents a fragmentary vertical sectional view of a cylinder block which contains the valve stem guide and valve shown on approximately full scale and showing the valve-stem packing or sealing means of the present invention partly in section; the parts of the internal combustion engine shown, being intended merely as representations of any conventional engine construction.

Figure 7 represents a section similar to that shown in Figure 6, though on a somewhat smaller scale, indicating a method by which the valve-stem packing or sealing means of the present invention may be applied to the valve-stem guide.

According to the present invention, retaining means designated generally by the numeral 7 and which may be called a "cage", is provided, having an upper portion 8 for receiving and confining a generally annular sealing member 9 or 9a and having lower engaging means 10 adapted for retaining engagement, gripping engagement 45 or interlocking engagement with a terminal portion 11 of any valve stem guide 12 (either the upper terminal portion or the lower terminal portion).

The upper portion 8 is formed generally with a side wall 12, which is preferably of a more or less cylindrical form, and an upper transverse terminal wall 13 which may be more or less right angularly disposed with respect to the side wall 12. A central aperture 14 is provided in the terminal wall 13, of a diameter slightly larger 55 60

than the diameter of the particular valve stem 15 which it is adapted to fit and which it is adapted to surround; the difference in diameters being such difference as will form a suitable working clearance together with such tolerances as may be necessary to accommodate the necessary manufacturing facilities or methods which may be employed for the production of the member 7.

10 The inner diameter of the more or less cylindrical side wall 12 may be made more or less the same as the diameter of the end surface 16 against which the sealing member 9 is adapted to bear, although some latitude in this regard is possible.

15 The lower guide-engaging portion 19 of the retaining member 7 is (in the particular embodiment herein shown) composed of a plurality of circumferentially distributed fingers 17 which may, as in the embodiment herein shown, be arranged as a part of the same (more or less) cylindrical surface, so that such fingers will in transverse cross-section be shaped like the arc of a circle, and will lie generally in the arc of the same circle. The fingers 17 are preferably arranged as fragmentary parts of a more or less cylindrical surface of somewhat larger diameters than the diameter of the side wall 12, with a slight transverse flange-like portion 18 intermediate of and inter-connecting the side wall 12 with the fingers or legs 17.

30 The free terminals of the fingers or legs 17 are curved inwardly to form slight inwardly extending claw-like flanges 19, which are arranged in generally concentric or coaxial relationship to the fingers or legs 17 as well as to the side-wall 12 and aperture 14 and which in transverse cross-section, however, may be slightly curved and slightly inclined, as indicated, for instance, in Figures 1, 3 and 4. The terminal corners 20 of the slight claw-like flanges 19 are made suitably sharp, so that these corners or rather the slight edge formed in these corners may serve to cut the annular groove 21 into the side-wall of the valve-stem guide 12 by relative rotation 35 of the cage 7 and valve stem guide 12 in a manner described more in detail hereinafter.

According to another phase of the present invention, suitable projection (or indentations) 22 may be provided either on the side-wall 12 or on the terminal wall 13 or some other part of the cage whereby interlocking engagement may be effected between the cage 7 and a suitable turning tool 23. By providing the slight ribs 22 in the general form indicated in the embodiment 50 of the invention herein shown, the turning tool 23 may be in the form of a socket wrench as indicated in Figure 7, having any suitable handle 24, whereby the cage 7 may be turned manually or otherwise after the socket wrench has been 55 superimposed upon the ribbed portion of the cage; the series of circumferentially distributed ribs defining between them a rectangle, triangle or any other suitable polygon, and the socket wrench being similarly formed in a manner conventional 60 in socket wrenches.

In the particular embodiment shown, the ribs 22 also serve to reinforce the cage and particularly to reinforce the legs 17 at their upper ends by providing a slight transverse bracing across 65 the slight flange 18 directly above each leg so as to minimize deflection of the legs at the place where they join the rest of the cage and to confine such deflection as may be caused in the leg, to the body part of the leg.

70 The cage 7 is preferably stamped and formed

out of a sheet of steel of suitable thickness and grade, by means of suitable stamping and forming dies and is then preferably tempered to give the legs 17 a desired resiliency or springiness so they will function as spring fingers and also to give the slight cutting edges sufficient hardness and permanence to enable them to cut the annular groove 21 in the side wall of the valve-stem guide. Thus, the slight cutting edges 20 should be sufficiently harder than the metal of which the valve stem guide is formed, that the cutting edges 20 will cut a clean groove 21 in the valve-stem guide when the cage is rotated in relation to the guide.

75 The valve stem packing or sealing means of the present invention may be applied to the valve stem guide by the means generally shown in Figure 7; including the socket wrench-like tool 23 and the guiding pin 25 having a suitable head 26. The diameter of the pin 25 is such as to permit 80 a neat sliding fit in the bore 27 of the valve-stem guide 12 and the head 26 being sufficiently small to repose within the recess 28 of the socket wrench 23. The cage 7 having the generally annular sealing member 9 assembled therein, is 85 then threaded onto the pin 25 and the resultant assemblage is then applied to the desired end of the valve-stem guide (from which the valve-stem has preferably been removed) in a manner shown in Figure 6, and the wrench 23 is then applied to the top of the cage and the cage forcibly pressed onto the valve-stem guide in an axial direction so as to spread the legs 17 of the cage (against the spring tension inherent in said legs) 90 until the generally annular sealing members 9 is 95 firmly pressed in an axial direction between the terminal surfaces 16 of the valve-stem guide and the inner surface of the terminal wall 13 of the cage. When the cage has been so superimposed upon the valve-stem guide to this extent, then, 100 without releasing the axial pressure upon the cage, the cage is turned several revolutions, thereby causing the slight cutting edges 20 to cut an annular groove into the outer surface of the valve-stem guide, and at the same time, embedding the claw-like flanges 19 of the spring-legs 17 in the groove thus formed, and establishing a generally permanent interlocking engagement between the cage and the valve-stem guide, with the generally annular sealing member 9 105 under axial compression. When the groove 21 is of sufficient depth, the wrench 23 is removed and the pin 25 is removed, and in place of the pin 25, the valve-stem 15 is reinserted into the position shown in Figure 5, or as also shown in 110 Figures 1, 2, and 3.

If desired, the periphery of the claw-like flanges 19 may be slightly relieved from the cutting corners or cutting edges 20, as for instance, by shaping such peripheral edges on a slightly 115 smaller radius than the radius of the valve stem guide which the cutting corners or edges 20 are intended to cut, so that the generally circular peripheral portions of the claw-like flanges which trail the cutting edges 20 when the gage is rotated, will be slightly relieved and thus permit of a more effective cutting operation. So too, if desired, a slight backward rake may be provided on the cutting corners, also to facilitate the cutting operation.

120 The claw-like flanges 19 may be disposed generally at a right angle to the spring legs 17 or at a right angle to the axis of the device, or they may be slightly inclined, as indicated particularly in Figures 1, 3, 4 and 6, whereby the axial 125

compression on the generally annular sealing member 9 may be increased slightly as the depth of the groove is increased, by virtue of the fact that the claw-like flange will give the entire cage 5 a slight camming action in an axial direction, tending to pull the cage further onto the valve stem guide as the depth of the groove is increased from the initial cut to the final depth of the groove.

10 The sealing member 9 may either be of a continuous or unbroken annulus, as for instance, formed by molding or by stamping or otherwise cutting the member 9 out of a solid piece of material, or the member 9 may be formed 15 continuously in the general manner of split packing rings, and perhaps formed of a continuous strip or band of material curved into a generally annular shape and with its ends in more or less abutting relation to each other, and also suitably 20 bevelled or inclined so as to form, in effect, a generally continuous annulus surrounding the valve stem 15. However formed, the outer diameter is made generally to conform to the inner diameter of the side wall 12 of the cage, while the inner 25 diameter is made generally to conform to the diameter of the valve-stem 15.

The sealing member 9 is formed of a more or less resilient material preferably including a fibrous body and a non-fibrous binder. In one 30 embodiment of the present invention, the sealing member 9 may be formed of a body of cotton or a body of asbestos or a mixture of the two, with a non-fibrous binder which may impregnate the fibrous body to a greater or lesser depth 35 either completely or partially.

If the body is formed of a strip of material, then a suitably braided or even a suitably twisted textile structure or strand may be used, formed of cotton or of asbestos or a mixture of the two, 40 while if the member is to be formed without any interruption, that is, without any "split" in its circumference, then it may be cut out of a sheet of woven or other textile formation of suitable thickness, either single ply or double ply, or 45 multi-ply, formed of common asbestos or a mixture of the two, or it may be molded or matted or felted out of these respective fibres or mixtures of the same.

The annular sealing member may be impregnated at any stage in its formation or after the annulus is finished, with any suitable oil-resistant binding material which preferably has suitable resiliency or at least which will not altogether 50 destroy the resiliency inherent in the fibrous body of the member 9. For such binding material, a resilient and oil-resistant amorphous organic material may be used, such as the synthetic organic materials known in the trade under 55 the trade-marks or trade names "Duprene" and "Thiokol", which are generally regarded as artificial or synthetic rubber but which, while possessing the generally amorphous and resilient characteristics of rubber, do not respond to the solvent or deteriorating action of oils and gasoline in the same manner as rubber does, and in fact, resist oil and gasoline to a substantial extent, and also resist heat to an extent suitable 60 for use in the valve-stem packing or sealing means of the present invention.

The impregnation may be, as stated, either throughout the mass of the fibrous body or it may be partially through such mass, and the proportions of binder and fibrous body may vary 70 in the finished member 9.

In the formation of the sealing member 9, graphite or other anti-friction material may be incorporated either in the fibrous body or in the binding material, or it may be applied to the surface of the sealing member 9 after the same has been formed, thereby to minimize friction between the bore of the member 9 and the surface of the valve stem 15.

In the sections of the member 9 shown in Figures 1, 2, 3, 5 and 6, variant formations are shown for the member 9, because, as stated, this member 9 may be formed of successive superimposed plies of woven, knitted or other textile formations (of cotton, or asbestos, or mixtures) as indicated generally in Figure 3, or may be formed 15 of felted fibrous masses, as indicated generally in Figures 5 and 6, or may be formed of braided, twisted, tubular woven or knitted, or flat woven or knitted and subsequently rolled textile strands or bands, (one form of which is illustrated in 20 Figure 1) which may be variously impregnated or filled with the binding material as mentioned. So too, the member 9 may be formed of the resilient and oil-resistant amorphous organic material mentioned, without any fibrous material 25 contained therein, or with the fibrous material mixed and compounded in the material itself, while the same is in a plastic state and before it is molded or formed to shape.

The valve-stem packing or sealing means of 30 the present invention is highly efficient and effective over a long period of time and under all operating conditions, as it is found that a good sealing contact is maintained between the bore of the sealing member 9 and the surface of the 35 valve-stem 15, without any appreciable wear and also without the development of any appreciable looseness between such member 9 and valve stem 15, and also that a substantially permanent contact is maintained between the end of the valve-stem guide and the juxtaposed surface of the sealing member 9. The permanence of these sealing contacts may be due partly to the tension initially set up in the spring legs 17, and due 40 partly to initial compression under which the annular sealing member 9 is placed, and perhaps also due to the slight tendency of the fibrous body to swell and also due to the absence of any substantial wear in the bore of the member. By the 45 valve-stem packing and sealing means of the present invention, the passage of oil from the crank case into the combustion chamber or into the gas intake passageways of the cylinder head is minimized, and also the intake vacuum in the combustion chamber is maintained at the maximum, because of the seal effected around the 50 valve stem.

In the particular illustration herein shown, the valve-stem packing and sealing means of the present invention is shown applied particularly to the end of the valve stem guide nearest the combustion chamber, although it is to be understood that the valve stem packing and sealing means of the present invention may also be 55 applied to the other end of the valve-stem guide.

The present invention may be embodied in other specific forms without departing from the spirit or essential attributes thereof, and it is therefore desired that the present embodiment 60 be considered in all respects as illustrative and not restrictive, reference being had to the appended claims rather than to the foregoing description to indicate the scope of the invention.

Having thus described the invention what is 75

hereby claimed to be new and desired to be secured by Letters Patent is:

1. Packing means for sealing the engaged surfaces of a valve stem and a guide therefor, said means comprising a metal cage having a portion forming a chamber at one end, a sealing member within the chamber adapted to engage the end of said guide and surround said stem, and a plurality of legs extending in a generally axial direction from said chamber-forming portion of the cage, each leg terminating in a radially inwardly directed claw having a hardened cutting edge, and all of said cutting edges being substantially concentric and co-planar, whereby rotation of the cage on the guide will rout a claw-receiving groove in the guide.
2. Packing means for sealing the engaged surfaces of a valve stem and a guide therefor, said means comprising a steel cage having a portion forming a chamber at one end, a sealing member within the chamber adapted to engage the end of said guide and surround said stem, and a plurality of legs extending in a generally axial direction from said chamber-forming portion of the cage, each leg terminating in a radially inwardly directed claw having a steel cutting edge, and all of said cutting edges being substantially concentric and co-planar, whereby rotation of the cage on the guide will rout a claw-receiving groove in the guide.
3. Packing means for sealing the engaged surfaces of a valve stem and a guide therefor, said means comprising a metal cage having a portion forming a chamber at one end, a sealing member within the chamber adapted to engage the end of said guide and surround said stem, and a plurality of legs extending in a generally axial direction from said chamber-forming portion of the cage, each leg terminating in a radially inwardly directed claw having a hardened cutting edge, all of said cutting edges being substantially concentric and co-planar, whereby rotation of the cage on the guide will rout a claw-receiving groove in the guide, and said cage having a non-circular cross-sectional shape adapted to receive a socketed tool for turning the cage on the guide and having a radial shoulder for receiving axial thrust of said tool.
4. A self-interlocking cage for operatively retaining a valve stem packing in position against an end of a valve stem guide, said cage including a chamber portion for receiving said packing, and a plurality of legs extending in a generally axial direction from said chamber portion and each terminating in an inturned claw-like flange portion provided with a cutting edge adapted to groove said guide upon rotation of said cage thereon, said flanges being inclined relative to the axis of said cage thereby to advance said cage axially on said guide as the depth of the groove is progressively increased.
5. A self-interlocking cage for operatively retaining a valve stem packing in position against an end of a valve stem guide, said cage including a chamber portion for receiving said packing, and a plurality of radially resilient legs extending from said chamber portion, said legs each terminating in an inturned terminal guide-cutting portion struck along a smaller radius than the radius of the corresponding valve stem guide portion to provide two cutting corners with a relieved portion therebetween, whereby said cage

will readily groove and interlock with said valve stem guide when rotated thereon in either direction.

6. A cage for operatively retaining a valve stem packing in position against the end of the valve stem guide, said cage including a chamber portion for receiving said packing, radially resilient legs extending from said chamber portion and having inturned terminal portions each interlocking engageable with a recess on the exterior of said valve stem guide, a portion of generally non-circular cross section adapted to receive a socketed tool, and a shoulder portion for receiving axial thrust of said tool.

7. In an apparatus for grooving the outer surface of a valve-stem guide, a cage having a portion adapted to radially and axially confine a generally annular sealing member, said cage having radially resilient fingers adapted to extend along the said guide and having terminal portions provided with cutting and engaging means, and said cage member having circumferentially distributed ribs adapted to be engaged by a tool and further having a shoulder adapted to be engaged by said same tool whereby said cage may be turned by said tool while axially thrust on said valve stem guide.

8. In an apparatus for generally permanently assembling a sealing means on a valve-stem guide, a cage member adapted to radially and axially confine a generally annular sealing member, said cage having radially resilient fingers adapted to extend along the valve-stem guide and having terminal portions provided with cutting and engaging means, said cage having circumferentially arranged means adapted to be engaged by a turning tool, whereby said cage may be turned by the tool to groove the surface of the valve-stem guide and to engage the cage therewith while exerting axial pressure on the cage.

9. In an apparatus for generally permanently assembling a sealing means on a valve-stem guide, a cage adapted to radially and axially confine a generally annular sealing member, said cage having radially resilient fingers adapted to extend along the valve-stem guide and having terminal portions provided with cutting means and engaging means, said cage also having means adapted to be engaged by a turning tool and having a shoulder adapted to be engaged by the tool to exert axial thrust on the cage during the turning movement, whereby said cage may be turned by said tool while being axially thrust onto said valve stem guide, thereby to groove said guide and to engage the cage therewith.

10. In an apparatus for generally permanently assembling a sealing means on a valve-stem guide, a cage adapted to radially and axially confine a sealing member and having radially resilient fingers adapted to extend along the valve-stem guide and having terminal portions provided with cutting means, said cage having circumferentially distributed ribs adapted to be engaged by a turning tool, said cage also having a shoulder adapted to be engaged by the same tool for exerting axial pressure on the cage during the turning movement whereby said cage may be axially thrust against and turned on said guide, thereby to groove the guide and engage the cage therewith.
